TRAIN DISPATCHING SYSTEM FOR RAIL-ROADS

Richard C. Leake, Rochester, N. Y., assignor to
General Railway Signal Company, Rochester,
N. Y.

Application April 25, 1929, Serial No. 358,075

15 Claims. (Cl. 246—3)

This invention relates to train dispatching systems of the synchronous selector type, and more particularly to means for increasing the number of uses to which a channel circuit may be put by stopping the system at a channel or channel point during its operating cycle.

In synchronous selector type train dispatching systems, suitable synchronously controlled contacts located at a dispatcher's office and at the various way stations along the railway track are used to make available a plurality of sequentially closed message circuits. In accordance with the present invention, it is proposed to give a distinctive indication at a way station when a particular channel circuit is closed for an appreciable period of time, as distinguished from the control given if such message channel is closed only for the usual stepping period. Another feature of the present invention resides in the energization of a relay located at a particular way station through a circuit local to said way station only in the event that the synchronous selector is caused to hesitate when a particular channel circuit is closed.

Other objects, purposes, and characteristic features of the present invention will in part be understood from the illustrations in the accompanying drawings and in part be pointed out in the description hereinafter.

In describing the invention in detail, reference will be made to the accompanying drawings, in which:

Fig. 1A shows conventionally the dispatcher's office equipment of one form of train dispatching system embodying the present invention;

Fig. 1B shows the apparatus at one way station of this same system, so that, if Figs. 1A and 1B are laid end to end they constitute a diagrammatic representation of the system; and

Fig. 2 shows on an enlarged scale a portion of the selector shown in Fig. 1A.

Structure.—Referring to Fig. 1B of the drawings, passing siding PS of a railway system having many passing sidings, is shown, to which the present invention has been applied. At the east end of this passing siding have been shown a main starting signal 2, and a dwarf-starting signal 2^d. The east end of the passing siding PS has a track switch, preferably operated by a switch machine SM. This track switch is protected by the usual detector track circuit including the track relay TR. The relays SR and SMR are used for controlling the signal 2 and the switch machine SM respectively, these relays SR and SMR being of the polar permanent mag-

net stick type, that is, these relays are operated into a position depending upon the polarity of the current applied thereto and remain in their last energized position even though de-energized, by reason of the action of permanent magnets 5 associated therewith. These relays SR and SMR are controlled through the medium of the control relay CR, which control relay CR is of similar construction, and is controlled through the medium of the synchronous selector SS¹. The dispatcher's office (see Fig. 1A) is connected with the various way stations through the medium of a stepping wire 3, a common wire C, a starting wire 4 and a message wire 5. At each way station is located a line relay, of which the line relay at the way station shown has been designated LR¹.

Referring now to the dispatcher's office equipment, which includes a miniature track layout conforming with the railway system to which the present invention is applied, and of which, for convenience, the miniature passing siding PS only has been shown. Associated with the east end of this passing siding PS is an indicating lamp I, which manifests by its illumination the occupancy of the detector track circuit at the east end of the passing siding PS. Also, associated with the east end of this miniature passing siding PS are levers L¹ and L², having an interlocking lock rod LR. These levers through 20 the medium of the synchronous selector system hereinafter described are adapted to control the switch machine relay SMR and the signal relay SR respectively (see Fig. 1B). In the dispatcher's office is provided a master synchronous selector 25 MSS, which in many respects is constructed like the synchronous selector SS¹, etc. located at the various way stations.

These selectors MSS and SS¹ include, a main shaft 10 driven by suitable spring driving means, such as a clock-work mechanism (not shown), include a rotating arm 11 and a rotating arm 11¹ respectively, escapement wheels 12 and 12¹ respectively, include pallets 13 and 13¹ respectively, and include magnets 14, 15, and 14¹, 15¹ respectively. The master selector MSS, is provided with a slip ring 16 engaging the rotating arm 11 and is provided with a slip ring 17 engaging the rotating contact segment 18, this contact segment 18 being insulated from the contact arm 11 by insulation 18^a, whereas the way station selector SS¹ is provided with a slip ring 19 engaging the rotatable arm 11¹. The way station selector SS¹ also includes a stop magnet 20, which, when energized, disengages the stop 55

latch 21 from the arm 11¹. This selector SS¹ also includes inertia members 22 and 23, of which the member 22 closes contacts 24-25 when the escapement pawl or pallet 13¹ is moved to its 5 extreme left hand position, whereas the inertia member 23 closes contact 23-26 and opens contact 23-27 when the pallet 13¹ assumes its extreme right hand position, this pallet 13¹ assuming either extreme position only in the event 10 that the corresponding magnets 14¹ or 15¹ are energized for more than a predetermined period of time. The responsiveness or selectivity of these contacts 24-25, 23-27, and 23-26 is in part 15 dependent upon the inertia of the inertia members 22 and 23 and in part due to the time required for the direct current and the resulting magnetism to build up in the magnets 14¹ or 15¹ to a maximum value. In the arrangement shown 20 no such inertia members have been shown for the selector MSS, but may be used when desired.

The line relay LR¹, heretofore mentioned, is also one of the polar permanent magnet stick type, constructed similarly to the relays CR, SR, and SMR. In the dispatcher's office is provided 25 a master relay MR having separate windings 30 and 31, for operating the contact 32 of this relay to either of its two extreme positions, this contact 32 remaining in the biased position to which it was last operated by a toggle spring 33. This master relay MR alternately applies positive and 30 negative potential across the stepping wire 3 and common return wire heretofore mentioned. The line relay LR⁰ in the dispatcher's office is operated by the potential applied across the stepping 35 wire 3 and common wire C, which line relay LR⁰ controls the escapement magnets 14-15 causing rotation of the synchronous selector MSS, which in turn controls the master relay MR by the alternate application of current to the coils 39 and 31, 40 so that these three devices MR, MSS, and LR⁰ are operated sequentially in rotation at a speed depending upon the inherent operating characteristics of these devices. The master selector MSS has also associated therewith a starting relay STR.

The indicating lamp I is controlled through the medium of indicating stick relays IR¹ and IR², these indicating stick relays IR¹ and IR² being dropped by energization of the cancelling relay 50 CAR, all in a manner to require two revolutions of the selector MSS before the relay IR¹ is dropped.

Having now considered the various elements of the system, it is believed expedient to consider 55 the operation of this system, in order to get a more clear understanding of the various operating characteristics and functions of the various devices.

Operation.—Attention is directed to the fact 60 that the system is normally at rest, and assumes the position shown, because the coil 30 of the master relay MR is de-energized, this being true because the contact arm 11 engages the stationary contact 40 and connects the positive terminal of battery 41 to the starting wire 4, but since the starting wire 4 and common wire C are not connected together there is no current flowing through coil 30, even though the upper terminal of this coil 30 is connected to the negative terminal of the battery 41 and the lower terminal of this coil 30 is connected to the common wire C. In this connection it should be noted that movement of either the lever L¹ or lever L², momentarily connects the common wire C to the contact 40 of the master selector MSS, thereby caus-

ing momentary energization of the coil 30 of the master relay MR through the following circuit:—beginning at the positive terminal of the battery 41, wire 42, slip ring 16, arm 11, stationary contact 40, wires 43, 44 and 39 elements 45-46-47-48, 5 or elements 49-50-51-52, depending upon whether the lever L² or L¹ respectively, have been operated, common wire C, wires 53 and 55, winding 30 of the master relay MR, wires 56 and 57, to the negative terminal of battery 41. With 10 this circuit momentarily completed, the contact 32 of the master relay MR is operated to its right hand extreme position, in which position it is held by the spring 33. Attention is also directed at this time to the fact, that lock arm 21 of the lock 15 magnet 20 of the synchronous selector SS¹ is now in its raised position.

Let us assume, that the lever L² was the one which was moved, and that it was moved to its lower extreme position, when the circuit just 20 traced was completed, and that it now assumes the same lower extreme position.

In order that the lever L² may be moved from its neutral position, the interlocking lock rod LR must be moved to its left hand dotted-line position, locking the lever L¹, so that it cannot be moved from its neutral position. This is necessary because the lever L¹ places negative potential upon the message channel for controlling the relay CR and the lever L² places positive potential 30 upon the message channel for controlling the relay CR. Hence, it is necessary, in order that the relay CR shall be controlled, and in order that no short circuits shall occur, that only one lever be moved at a time. With the contact 32 of the 35 master relay MR now assuming its right hand dotted position in response to momentary closure of the circuit for the coil 30 of this relay MR, positive potential is applied to the stepping circuit and to the various line relays such as relays LR⁰ 40 and LR¹ in multiple, through the following circuit:—beginning at the positive terminal of the battery 60, wire 61, contact 32 of relay MR, wire 62, stepping wire 3, the line relays LR⁰, LR¹, etc. in multiple to common wire C, wires 53, 63, 64, and 45 97, to the mid point of battery 60. Completion of this circuit causes the line relays LR⁰ and LR¹ to be moved to their right hand extreme position, thereby causing the escapement pallets 13 and 13¹ to be moved to the right by completion of the 50 following two circuits:—(1) beginning at the positive terminal of battery 65 (see Fig. 1A) wire 66, contact 67, in a right hand position, wire 68, electro-magnet 15, wires 59 and 69 to the negative terminal; and (2) beginning at the positive 55 terminal of battery 70, wire 71, contact 72 of the line relay LR¹ in its right hand position, wire 73, winding of the electro-magnet 15¹, wires 74 and 75 to the negative terminal of the battery 70. The escapement pallets 13 and 13¹ are thus both moved 60 to their right hand position thereby allowing the contact arms 11 and 11¹ to move one step into engagement with the stationary contacts 76 and 77 respectively. With the pallet 13¹ now assuming its right hand position the slow-acting contacts 24 and 25 are opened, the lock magnet 20 65 is de-energized and the latch 21 in response to gravity or a suitable spring, assumes its latching position. In the event the arm 11¹ has lost a step in the preceding revolution, it will be held in 70 the zero position until the next long impulse is applied to the magnet 14¹ at which time the lock magnet 20 will release the contact arm 11¹, thus re-synchronizing the arm 11¹ with the arm 11. With the contact arm 11 engaging the stationary 75

contact 76, the following circuit for the coil 31 of the master relay MR is energized through the following circuit:—beginning at the positive terminal of the battery 41, wire 42, slip ring 16, rotatable arm 11, stationary contact 76, wires 79 and 80, winding of the coil 31, wires 81 and 57, back to the negative terminal of the battery 41. Current flow in this circuit causes the contact 32 of this master relay MR to be moved to its left hand position, and in turn causes the line relay LR⁰ and LR¹ to assume their left hand position, thereby causing the following two circuits to be closed:—(1) starting at the positive terminal of battery 65, wire 66, contact 67 in a left hand position, wire 82, electro-magnet 14, wire 69, back to the negative terminal of battery 65; and (2) starting at the positive terminal of battery 70, wire 71, contact 72 in a left hand position, wire 84, electro-magnet 14¹, wire 75, back to the negative terminal of battery 70. These circuits result in the operation of the pallets 13 and 13¹ to their left hand position, and again allowing the contact arms 11 and 11¹ to take their next step. It is thus seen, that with the system once initiated, the arms 11 and 11¹ will operate step by step in synchronism until the arm 11¹ engages the stop arm 21 to hold it there until the arm 11 of the master synchronous selector MSS engages the contact 40, which stops the mechanism on that contact 40 as it is not directly connected to the magnet 30 of the master relay MR, as are the remaining contacts of even position of the master selector MSS.

Let us now be reminded, that the lever L² has been moved to its lower extreme position, with the lock rod LR in its left hand position to lock the lever L¹ against movement and to unlock the lever L². Bearing in mind now, that the lever L² assumes the lower extreme position, the following message circuit is closed when the contact arms 11 and 11¹ assume the 5th position, beginning at the positive terminal of a battery 85, wires 86 and 87, contacts 99 and 89, wires 90 and 91, contact 5th, contact segment 18, slip ring 17, wire 92, through message wire 5 to the way station shown in Fig. 1B, wire 93, slip ring 19, arm 11¹ of selector SS¹, contact 5th of selector SS¹, wires 94 and 95, winding of control relay CR, wire 96, to the common return wire C, wires 53, 63, and 54, to the mid-point of battery 85. Momentary closure of this message circuit causes the polar contact 104 of the control relay CR to be moved to its right hand position and causes the neutral contact 108 to assume an energized position. Since the synchronous selectors MSS and SS¹ do not hesitate or stop and stay at the contact 5th, the inertia member 23 is not operated and for this reason the signal relay SR remains in or is operated to the left hand position.

It will be noted here, that the polar contact 104 of relay CR is moved to its respective extreme position in response to the energization of relay CR, before the neutral contact 108 of the relay CR assumes its energized position, which is an inherent characteristic of polar neutral relays. Hence, potential is placed upon the function relay to be controlled as selected by polar contact 104, only after said polar contact 104 has assumed its proper position for selecting said function relay to be controlled. Also it will be noted, that if the synchronous selector SS¹ pauses at the contact 5th for a period of time greater than the normal total channel time, that a positive potential is placed upon contact 108. However, if the selector SS¹ does not pause at contact 5th, a negative poten-

tial is placed upon the contact 108 of relay CR. These polarity potential determinations are governed by the inertia member 23 as hereinafter explained.

As the inertia member 23 is not operated to a right hand position due to hesitation of selector SS¹, but remains in its biased left hand position, a negative potential is placed upon the relay SR during a second part of the normal total channel time after the polar contact 104 and the neutral contact 108 of relay CR assume their energized positions. This circuit for energizing the relay SR is momentarily completed, which is traced as follows:—beginning at the negative terminal of battery 100, through wire 101, contacts 27—23, 15 wire 102, slip ring 19, arm 11¹ of selector SS¹, stationary contact 5th, wires 94 and 103, neutral contact 108 of the control relay CR, wire 109, contact 104 assuming its right hand position, wire 105, winding of the signal relay SR, wires 106, 107 20 and 111, to the mid-point of the battery 100. It is thus noted, that movement of lever L² to its lower extreme position did not move the polar contact of the signal relay SR.

Let us now assume that the lever L² is moved 25 to its raised position. It is of course noted that the movable contact 47 of this lever is momentarily connected to one of the stationary contacts 40, thereby momentarily energizing the coils 30 of the master relay MR for reasons heretofore explained, 30 thereby starting the synchronous selector system from rest.

Also, it should be noted, that movement of the lever L² to its raised position opens the contacts 118—149 thereby disconnecting the stationary 35 contact 110 of the master selector MSS from the coil 31 of the master relay MR, so that the master relay MR is not operated when the master selector MSS reaches the 5th position, and for obvious reasons the synchronous selector SS¹ is also 40 stopped at the 5th position with the arm 11¹ engaging the stationary contact 5th. With the selector SS¹ maintained in this position for an appreciable period of time the pallet 13¹ is moved to its extreme right hand position, in which position contacts 23—27 are open and contacts 23—26 45 are closed, and since the control relay CR still assumes its right hand position, because the same polarity is applied to control relay CR when the lever L² assumes either its upper or its lower extreme position, the following circuit is closed for the signal relay SR, which operates the signal relay SR to its right hand dotted position:—beginning at the positive terminal of the battery 100, wire 112, contacts 26—23, wire 102, slip ring 55 19, contact arm 11¹, contact 5th, wires 94 and 103, contact 108, wire 109, contact 104 in its right hand position, wire 105, winding of the signal relay SR, wires 106, 107, and 111 to the midpoint of the battery 100. The closure of this circuit operates the signal relay SR to its right hand position, thereby clearing the signal 2, providing traffic conditions in advance are closed, through a circuit readily traced in the drawings.

After holding the lever L² in its raised position 65 for a sufficient period of time to allow the contacts 23—26 to close and the relay SR to respond to such closure, the operator may return the lever L² to its neutral position, thereby closing the following circuit for the coil 31 of the master 70 relay MR:—beginning at the positive terminal of the battery 41, wire 42, slip ring 16, contact arm 11, stationary contact 110, wire 113, contacts 114—115, wire 116, contacts 119—118, wires 117 and 60, coil 31 of the master relay MR, wires 81 75

and 57, back to the negative terminal of the battery 41. With this circuit closed, the synchronous selectors MSS and SS¹ assume their stepping operation until they have completed their cycle of operation.

Let us now observe, how dropping of the track relay TR at one of the distant way stations, such as the way station shown in Fig. 1B, causes the synchronous selector system to remain in operation so long as such track relay TR is de-energized, to thereby insure the transmission of the proper indication when the track relay is re-energized. Let us also observe, how the fact that a particular track relay TR is de-energized, is manifested in the dispatcher's office.

Let us assume that the track relay (see Fig. 1B) is de-energized. With this track relay TR de-energized and the synchronous selectors MSS and SS¹ assuming their normal zero position, the following circuit for the coil 30 of the master relay MR is closed:—beginning at the positive terminal of the battery 41, wire 42, slip ring 16, arm 11, stationary contact 40, wires 43, 44, and 120, winding of the starting relay STR, wires 121 and 122, starting wire 4, wire 123 (see Fig. 1B) stationary contact 124, arm 11¹, stationary contact 125, wire 126, back contact 127 of the track relay TR, wire 128, common return wire C, wires 53, 55, magnet 30 of the master relay MR, wires 56 and 57, back to the negative terminal of the battery 41. With this circuit closed, the starting relay STR will close its front contact 129 after a short interval of time, thereby shunting its own winding and allowing sufficient current to flow to cause the master relay MR to move its contact 32 to its right hand position, thereby initiating the synchronous selector MSS from its zero position. In this connection, it may be pointed out that the starting relay STR, is purposely made slow-acting so that as one cycle of operation is completed and the next cycle of operation of these synchronous selectors MSS and SS¹ is started there is a sufficient hesitation at the zero position to allow the various selectors equipped with lock magnets 20 to have their lock magnets energized in response to the slow-closing contacts 24—25.

Also, in this connection it is desired to point out that in the event that a particular rotating arm, such as selector arm 11¹ has lost a step or two and has not reached its zero position, the lock arm 21 will be raised during the period of hesitation obtained by the slow-acting starting relay STR, and immediately dropped as the first step has occurred, so that the arm 11¹ of this synchronous selector is not permitted to leave its zero or starting position when it reaches it, until the beginning of the next cycle of operation of the system. In other words, the purpose of the lock magnet 20, which is operated only in the event that the line relays assume their left hand position for more than a predetermined period of time, is to bring the various selectors into synchronism, in the event one or more thereof get out of step by reason of some external influences, such as lightning disturbances, or the like. It should now be remembered that the track relay TR is de-energized and that the synchronous selector system remains in operation so long as the back contact 127 of this track relay TR remains closed, the various selectors, such as selector SS¹, being resynchronized each time a new cycle of operation is started. During each revolution of the arms 11 and 11¹ of these synchronous selectors MSS and SS¹, while the track

relay TR is de-energized, the following circuit for the indicating relay IR¹ is momentarily completed:—beginning at the negative terminal of the battery 85, wires 130, 131 and 132, upper winding of the relay IR¹, wire 133, the sixth stationary contact of the selector MSS marked 6th, segment 18 of the arm 11, slip ring 17, wire 92, message wire 5, wire 93, slip ring 19, rotatable arm 11¹, contact 6th of selector SS¹, wire 134, back contact 135 of the track relay TR, wires 136 and 128, common wire C, wire 53, 63, 64, and 54, to the midpoint of the battery 85. Momentary completion of this circuit causes the indicating relay IR¹ to assume its energized position, thereby closing the following stick circuit for this relay IR¹, which stick circuit includes the upper winding of the relay IR²:—beginning at the positive terminal of the battery 41, wires 138 and 139, contact 148 of relay CAR, wire 141, front stick contact 142 of the relay IR¹, wire 143, lower winding of this relay IR¹, wire 144, upper winding of the indicating relay IR², wires 145 and 146, back to the negative terminal of the battery 41. With this circuit closed the indicating relay IR² also assumes its energized position, thereby closing its own stick circuit which may be traced as follows:—beginning at the positive terminal of battery 41, wires 138 and 139, contact 147, of the relay CAR, wire 148, front stick contact 149 of the relay IR², wire 150, lower winding of the relay IR², wires 151, 145, and 146, back to the negative terminal of the battery 41. It will be noted that energization of the indicating relay IR² through the medium of its front contact 152 closes an energizing circuit for the indicating lamp I. Also, it will be noted that at the end of the first revolution of the master selector MSS the indicating relay IR¹ is de-energized by reason of operation of the cancelling relay CAR to its left hand and then to its right hand position, and that the indicating relay IR² is de-energized at the end of the second revolution of the master selector MSS by operation of the cancelling relay CAR to its left and then to its right hand position all in a manner as more clearly explained in connection with the relays CR, IN, and IR in my prior application Ser. No. 332,132, filed January 12, 1929, now Patent No. 1,794,628 granted March 3, 1931, to which reference may be made for other features of the synchronous selector system.

Attention is directed to the fact that the indicating relay IR¹, of course, will not be de-energized at the end of the first revolution as just mentioned unless the track relay TR at the way station (see Fig. 1B) has in the meantime assumed its energized position. In this connection it should be noted that when the track relay TR does assume its energized position, the synchronous selector system will operate for at least one complete revolution after this track relay TR has assumed its energized position, because in this event the common wire and starting wire are connected together through the following partial circuit:—beginning at the starting wire, wire 155, back contact 156 of the relay IR¹, wire 157, front contact 158 of the relay IR², wire 159, to the common wire C, so that the coil 30 of the master relay MR is energized while the master selector MSS assumes its zero position by current flowing through the partial circuit just traced. The relay IR² is of course deenergized at the end of this cycle thus bringing the apparatus to a stop until again initiated by either the movement of a lever, the dropping of a track

relay or the happening of some other event that is to be indicated in the dispatcher's office.

Summary.—Without tracing the various circuits in detail it should be noted that the operation of lever L^1 from its neutral position applies negative potential to the control relay CR over its respective message channel. Also, the movement of lever L^2 from its neutral position applies positive polarity to the control relay CR over its respective message channel which is identical to the message channel used for lever L^1 . It should be noted that, as either of the levers L^1 or L^2 are operated to a lower extreme position the synchronous selector system will not hesitate or stop when it reaches its 5th stepping position, but that the synchronous selector will stop when it reaches its 5th stepping position when either the lever L^1 or L^2 are moved to a raised extreme position. It should be further noted, that the system does not hesitate at any contact when initiated by a way station, unless in response to the movement of a control lever simultaneously therewith or thereafter during the same cycle or cycles initiated by the way station.

25 In other words, the lever L^1 moved to a raised extreme position, energizes the control relay CR with negative potential, and causes the synchronous selectors to hesitate at the particular message over which the control relay CR is energized, 30 thus energizing the relay SMR with positive potential. With lever L^1 moved to a lower extreme position the control relay CR is energized with negative potential, but the system is not caused to hesitate at the respective message channel for energizing the relay CR, and the relay SMR is energized with negative potential. Also, with the lever L^1 in a neutral position there is no potential applied to the message channel for controlling the relay CR, which results in the fact that no 40 energy may be applied to either relay SR or relay SMR due to hesitation or non-hesitation of the synchronous selector SS¹, inasmuch as the neutral contact 103 of relay CR is not in an energized position.

45 When the relay SMR is energized with positive potential, it causes the switch machine SM to unlock its track switch and operate it to its normal position; but when the relay SMR is energized with negative potential, it causes the switch machine SM to unlock its track switch and operate it to its reverse position. This control has merely been indicated in order to simplify the disclosure.

Also, with lever L^2 moved to a raised extreme position positive potential is placed upon the control relay CR over its respective message channel, and the synchronous selectors are caused to hesitate at the respective message channel for the control relay CR, which energizes the signal relay SR with positive potential. With the lever L^2 moved to a lower extreme position, positive potential is placed upon the control relay CR over its respective message channel, but the synchronous selectors are not caused to hesitate, which 65 causes negative potential to be placed upon the signal relay SR. Also, with lever L^2 in a neutral position the relay CR is not energized, hence the relay SR or the relay SMR may not be energized with either positive or negative potential, due to the hesitation, or non-hesitation of the synchronous selector SS¹.

70 When the relay SR is energized with positive potential, it causes the signal 2 to be cleared, but when the relay SR is energized with negative potential, it causes the signal 2 to be held at stop.

This control has merely been indicated in order to simplify the disclosure.

It will be reiterated here, that the polar contact 104 of relay CR is sufficiently quick acting, so that the relay SR or SMR may not be operated before the control relay CR itself has been operated to a proper position. It will also be noted, that both the relays SR and SMR are sufficiently quick acting to operate after the relay CR has been operated during either a total 10 channel time of the normal rate, or during a total channel time including a hesitation time period. These relays SR and SMR are of the permanent magnetic stick type so that their contacts remain in their last actuated positions 15 although the current which controls them is only momentarily applied to their operating windings. Thus, the switch machine and signals are maintained in accordance with the positions of the control levers.

20 With a system arranged in accordance with the above described organization, it is readily apparent that a large number of channel circuits may be sequentially closed by step-by-step means synchronously operated at a central office and at 25 a large number of way stations. Also, that each of these channel circuits may be rendered available to carry out any one of four distinctive purposes. More specifically, these distinctive conditions which may be set up over a channel circuit 30 include a short positive impulse, a long positive impulse, a short negative impulse, and a long negative impulse. These distinctive conditions are respectively set up by the lever L^2 in a lowered position, by the lever L^2 in a raised position, 35 by the lever L^1 in a lowered position, and by the lever L^1 in a raised position. Such an arrangement provides that a given number of steps taken by a step-by-step means at a central office and at a large number of field stations will provide 40 a greater number of distinctive controls than would ordinarily be provided by a system having such a number of steps.

Having thus shown and described one particular embodiment of the present invention and having shown specific arrangements for carrying out the various functions of the present invention, particularly the functions of operating a large number of selective control devices over a single channel circuit of a synchronous selector system, 50 it is desired to be understood that the particular system selected has been selected for the purpose of facilitating disclosure of the nature and operating characteristics of the present invention, and has not been selected for the purpose of disclosing its scope or the exact structure preferably employed in practicing the same, and that various changes, modifications and additions may be made to adapt the invention to the particular problem encountered in practicing the same, all 55 without departing from the spirit or scope of the invention, except as demanded by the scope of the following claims.

What I claim as new is:—

1. A train dispatching system comprising, a 65 dispatcher's office, a distant way station, a synchronous selector at said dispatcher's office, another synchronous selector at said way station, means for operating the two mentioned synchronous selectors in synchronism, a plurality of 70 message circuits each including the same line wire and closed sequentially during operation of said selectors, a polar control relay in a particular one of said message circuits energized in response to the polarity of current flowing in said 75

message circuit, and a supplemental control relay of the permanent magnet stick type controlled in accordance with the period of time said polar control relay is energized.

- 5 5. A train dispatching system comprising, a dispatcher's office, a distant way station, a synchronous selector at said dispatcher's office, another synchronous selector at said way station, means for operating the two mentioned synchronous selectors in synchronism, a plurality of message circuits each including the same line wires and closed sequentially during operation of said selectors, a polar control relay included in a particular message circuit energized in response to the polarity of current flowing in said message circuit, and two supplemental control relays controlled in accordance with the position assumed by said polar relay and the time period through which said particular message circuit is energized.
- 10 20. 3. A train dispatching system of the selector type comprising, a single pair of line wires connecting a central office and a plurality of field stations, means for transmitting from said central office to said field stations a series of impulses each impulse of which may be of any one of four distinctive characters, control means at said field stations distinctively responsive to said impulses, step-by-step mechanism at said office and at each of said field stations for steering said impulses from the proper transmitting means to the proper control means, and traffic controlling devices controlled by said control means.
- 15 4. A train dispatching system of the selector type comprising; a single pair of line wires connecting a central office and a plurality of field stations; means for transmitting from said central office to said field stations a series of impulses each impulse of which may be either a short impulse of positive polarity, a long impulse of positive polarity, a short impulse of negative polarity or a long impulse of negative polarity, step-by-step means at said office for controlling said transmitting means and step-by-step means at each of said stations each operated one step for each impulse irrespective of its character, control means at each of said field stations selected by said step-by-step means and responding distinctively to certain of said impulses; and traffic controlling devices controlled by said control means.
- 20 50. 5. A train dispatching system of the selector type comprising; a single pair of line wires connecting a central office and a plurality of field stations; step-by-step means at the office and at each field station to define impulse periods, means controlled by said step-by-step means for transmitting from said central office to said field stations a series of impulses, one impulse during each impulse period, each impulse of which may be either a short impulse of positive polarity, a long impulse of positive polarity, a short impulse of negative polarity or a long impulse of negative polarity; control means at each of said field stations controlled by the step-by-step means at such station and responding distinctively to said impulses and which may assume any one of four different conditions depending on the character of a particular impulse; and traffic controlling devices at each of said field stations controlled by the said control means at such field station.
- 25 70. 6. In combination, a control office, a plurality of field stations, a line circuit connecting said control office and said field stations, step-by-step means at said control office and at each of said field stations all operated synchronously step-by-step through cycles of operation, means at the

control office for selectively applying impulses of positive and/or negative character to said line circuit for certain of said steps of said step-by-step means, and means at said field stations for selectively closing one or the other of two local channel circuits for each of said certain steps of said step-by-step means depending upon the polarity characteristics of the impulses of said line circuit for those steps, said local channel circuits being controlled by said step-by-step means and being closed only when said step-by-step means is operated to the corresponding step.

5 7. In combination, a control office, a plurality of field stations, a line circuit connecting said control office and said field stations, step-by-step means at said control office and at each of said field stations all operated synchronously through cycles of operation, means at the control office for selectively applying impulses of positive and/or negative character to said line circuit for certain steps of said step-by-step means, two local channel circuits for each of said certain steps of step-by-step means at said field stations and closed only during the corresponding step, and means at said field stations responsive to the polarity of the impulses on said line circuit for each of said steps to determine which one of said two channel circuits for that step shall be used.

10 8. In combination, a control office, a plurality of field stations, a line circuit connecting said control office and said field stations, step-by-step means at said control office and at each of said field stations, means for causing all of said step-by-step means to operate synchronously step-by-step through cycles of operation, means at said control office for selectively determining the time said step-by-step means remain on certain steps of a cycle of operation, means at the control office for applying impulses of selected polarity to said line circuit for certain of said steps, two local channel circuits for each of said steps of said step-by-step means at said field stations, means at said field stations responsive to the polarity of the impulse on said line circuit for each of said steps to determine which one of two channel circuits for that step shall be used, and means distinctively energizing each of said selected channel circuits in accordance with the selected duration said step-by-step means remain on the corresponding step.

15 9. In combination; a step-by-step means operable through a particular series of steps for any number of cycles of operation; a plurality of channel circuits prepared by said step-by-step means, one for each of certain steps of said step-by-step means; means for dividing each of said channel circuits into a plurality of branches; and remotely controlled means controlled in accordance with the polarity of an impulse for selecting for use during any particular cycle of operation only a particular branch of each of said channel circuits.

20 10. In combination, a step-by-step means operable through a particular series of steps for any number of cycles of operation, a channel circuit prepared on a particular step by said step-by-step means, remotely controlled means controlled in accordance with the character of a current impulse for dividing said channel circuit into a plurality of branches only one of which can be selected for use during any particular operating cycle, and remotely controlled means for distinctively energizing the selected

branch in accordance with another character of the same impulse.

11. In a selector type system for controlling traffic over railroads, a line circuit connecting a control office and a plurality of field stations, step-by-step means at the control office and at each of the field stations all operated synchronously step-by-step through cycles of operation, means at the control office for selectively im-
10 pressing impulses of positive and negative character on said line circuit for certain steps of the step-by-step means at the office, means at the control office for selectively determining the long and/or short duration of said certain steps of
15 said step-by-step means, and means at each of said field stations selectively controlled by the step-by-step means at said station and in accordance with the long and/or short duration of said certain steps and the positive and/or negative character of said impulses for said steps.

12. In a selector type system for controlling traffic over railroads, stepping and message line circuits connecting a control office and a plurality of field stations, step-by-step means at the control office and each of the field stations responsive to impulses on said stepping line circuit to operate in synchronism, means at the control office for selectively prolonging certain of said impulses on said stepping circuit, means at the control office for transmitting distinctive impulses over said message circuit on said steps, timing means at said field stations distinctively responsive to said prolonged impulses, message receiving means at said field stations responsive to said distinctive impulses on said message circuit, and means at each field station jointly controlled by said timing means and said message receiving means at such field station.

13. In a centralized railway traffic controlling system of the multiple impulse type for transmitting distinctive electrical impulses over a line circuit connecting two spaced stations, the combination with a line circuit, means for causing a series of impulses of current to flow in said line circuit which are distinctive both as to polarity and duration, means distinctively responsive to the polarity of a particular impulse of said series of current impulses, slow-acting means distinctively responsive to the duration of said particular impulse of current and operated to one position for a particular impulse if

the impulse is of long duration and which remains in its normal position if said impulse is of short duration, a polar relay, and a control circuit for said polar relay energized only by current of one polarity when said slow acting means is in one position and energized only by current of the reverse polarity when said slow acting means assumes the other position.

14. In a centralized traffic controlling system for railroads, a central office and a plurality of field stations, a line circuit connecting said office and field station, control contacts in said office, electro-responsive devices at each field station, step-by-step means at said office and at each field station for synchronously connecting control contacts and electro-responsive devices to said line circuit and controlled by impulses on said line circuit irrespective of their polarity or duration, said control contacts applying to said line circuit impulses of distinctive polarities and distinctive durations, one of said electro-responsive devices being distinctively controlled in accordance with the polarity of a particular impulse and another electro-responsive device being distinctively controlled in accordance with the duration of such impulse, and traffic controlling apparatus controlled by said one and said another electro-responsive devices.

15. In a centralized traffic controlling system for railroads, a central office and a plurality of field stations, a line circuit connecting said office and field station, control contacts in said office, electro-responsive devices at each field station, step-by-step means at said office and at each field station for synchronously connecting control contacts and electro-responsive devices to said line circuit and controlled by impulses on said line circuit irrespective of their polarity or duration, said control contacts applying to said line circuit impulses of distinctive polarities and distinctive durations, one of said electro-responsive devices being distinctively controlled in accordance with the polarity of a particular impulse and another electro-responsive device being distinctively controlled in accordance with the duration of such impulse, a switch controlled by said one electro-responsive device, and signals controlled by said another electro-responsive device.

RICHARD C. LEAKE. 50
